(57) CLAIM

I claim the ornamental design for a star-shaped bottle cap remover, as shown and described.

DESCRIPTION

FIG. 1 is a front left perspective view of the design for a star-shaped bottle cap opener showing my new design.

FIG. 2 is a rear right perspective view thereof.

FIG. 3 is a front elevation view thereof.

FIG. 4 is a rear elevation view thereof.

FIG. 5 is a top plan view thereof.

FIG. 6 is a bottom plan view thereof.

FIG. 7 is a left side elevation view thereof; and,

FIG. 8 is a right side elevation view thereof.
